EXERCISING MACHINE

Isabelle M. Caplan, Miami Beach, Fla.

Application July 13, 1934, Serial No. 734,917

6 Claims. (Cl. 128—25)

This invention relates to new and useful improvements in an exercising machine.

The invention has for an object the construction of an exercising machine which is characterized by the provision of a pair of upper pedals adapted to be gripped with the hands, a pair of lower pedals adapted to partially support a person by the person resting the feet thereon while sitting on some support, and an arrangement for causing rotations of said pedals so as to exercise the person by causing the arms and legs to go through circular motions.

Still further the invention proposes to so arrange the exercising machine that it is provided with a heavy base adapted to properly support the machine in a vertical position when a person works thereon, or to construct the base so as to be attachable on a floor.

Still further the invention contemplates to so construct the exercising machine that it is portable and may be placed near a wall or a window sill or placed so that the person exercising may be partially supported by said or other foreign objects.

Still further the invention proposes to so arrange the mechanism for rotating the pedals as to be located within a frame of the machine so that no moving parts outside of the pedals are exposed.

Still further the invention proposes to arrange the frame with a pair of vertical side pipes constituting the sides of the frame, and to arrange the driving mechanism to extend through one of the pipes.

Still further the invention also contemplates the provision of a motor for operating the device, said motor to be connected with the device by the provision of a belt arranged in such a manner that slipping is possible so that the person, in the event of emergency, can press heavily against the pedals and hold the machine from operating and so prevent accidents.

Still further the invention also proposes an arrangement whereby the frame of the machine may be adjusted to various tilted positions so as to exercise various muscles of the body during the natural exercising of the machine.

Still further the invention proposes the construction of a machine as mentioned which is simple and durable and which may be manufactured and sold at a reasonable cost.

For further comprehension of the invention, and of the objects and advantages thereof, reference will be had to the following description and accompanying drawing, and to the appended

claims in which the various novel features of the invention are more particularly set forth.

In the accompanying drawing forming a material part of this disclosure:—

Fig. 1 is a perspective view of a machine constructed according to this invention and illustrated with a person exercising thereon.

Fig. 2 is a rear elevational view of the machine illustrated in Fig. 1.

Fig. 3 is a fragmentary transverse vertical sectional view of one of the side arms of the frame of the machine.

Fig. 4 is a horizontal sectional view taken on the line 4—4 of Fig. 3.

Fig. 5 is a fragmentary enlarged detailed view 15 of a portion of Fig. 2.

Fig. 6 is a front elevational view of a machine similar to that illustrated in Figs. 1 to 5 except modified with an arrangement wherein the frame of the machine may assume various inclined positions.

Fig. 7 is a fragmentary enlarged sectional view taken on the line 7—7 of Fig. 6.

The exercising machine according to this invention comprises a heavy base 10 upon which is mounted a frame 11 consisting of a pair of vertical side pipes 11^a and a horizontal pipe 11^b. The base 10 is formed with several openings 10^a for screws by which it may be attached upon the floor. If intended to be attached it may be constructed relatively light since it need not support the machine in a vertical position.

The side pipes 11^a are equipped with flanges 12 upon the bottom ends which are attached upon the base 10. The side pipes 11^a have upper bushings 11^c slidable on the outer sides thereof and lower T connections set into the sides thereof. Horizontal pipes 13 and 13' are connected between these bushings and T connections respectively and form housings for upper and lower horizontal shafts 14 and 15 respectively. These shafts extend from the outer ends of the parts 11^c and 11^d which have plugs 16 mounted upon the outer sides. The outer ends of the shafts 14 and 15 are equipped with cranks 18 having pedals 19 upon 45 the ends thereof.

The bottom horizontal pipe 13' is formed of two sections engaging into opposite sides of a speed reduction unit 20. This speed reduction unit is provided with a shaft 21 extending from the rear side and provided with a pulley 22. A belt 23 connects with this pulley and connects with a small pulley 24 upon the shaft of the motor 25 which is mounted upon the base.

The shafts 14 and 15 are provided with sprock-

ets 26 and 27 arranged within the parts 11^c and 11^d at one of the sides of the frame. A chain 28 engages through one of the pipe sections 11^a and engages the sprockets 26 and 27. The bushings 5 11^c are slidably arranged upon the pipe sections 11^a. They are held in adjusted fixed positions with clamp screws 11^e threadedly engaging through the bushings and engaging against the pipe sections. The sides of the pipe sections 11^a 10 are formed with slots 11^f through which the shaft 14 extends. The sections 11^a are also formed with slots 11^g at the fronts which align with smaller openings 11^h in the bushings 11^c so that it is possible to inspect the interior of the pipe sections 15 11^a. The inspection is particularly intended to permit inspection of the sprocket 26 and the chain 28. The purpose of the vertical adjustment of the bushings 11^c is to compensate for wear on the sprockets and so as to adjust the tension 20 of the chain 28. The pipe sections 11^a are made from sections joined together with conventional unions 11ⁱ.

Details of the gear reduction 20 will not be given in this specification since they form no 25 part of the invention and gear reductions are generally known. The only requisite of the gear reduction is that driving of the shaft 21 is transmitted to rotate the shaft 15 at greatly reduced speed. A switch 31 is shown mounted upon one of 30 the pipes of the frame and is intended to be connected not shown with the motor 25 and a source of current for operating the motor. The details of this electric connection will not be given in this specification since they form no part of the invention and such connections are generally known. The arrangement must be such that when the switch 31 is closed to start the motor, and when the switch 31 is open, the motor ceases 35 its operation.

40 The operation of the device is as follows:—A person desirous of exercising upon the machine steps upon the bottom pedals 19 and holds the upper pedals 19 with the hands. Then one hand is taken off one of the pedals and the switch 31 45 operated to cause operation of the motor 25 and the hand is then immediately reengaged upon the pedal. Operation of the motor 25 will serve to drive the shaft 15 to cause the bottom pedals 19 to rotate continuously, and this rotation is 50 transmitted to the upper shaft 14 which causes the upper pedals 19 to similarly rotate.

55 Preferably the upper cranks 18 are set 180° from each other, and the lower cranks are similarly set relative to each other. If a person desires, when so exercising he or she may sit upon a window sill or rest with the back against a wall or lightly sit upon a table, though after continuous use of the device it will be found that much additional support is unnecessary.

60 In Figs. 4 and 5 a modification of the invention has been disclosed wherein an arrangement is provided to enhance the exercising value of the device. The arrangement is such that the frame 65 of the machine may be set at various inclined positions so that the operator is at an inclination and must strain certain muscles to maintain himself or herself upon the machine. This causes exercising of the muscles. The machine may be set to tilt in one or the other direction if it is 70 desired.

75 More particularly, the gear reduction mechanism 20 is provided with a casing 29 having a side wall 29^a equipped with a disc 33 by which the casing is swivelly mounted. The disc 33 is

supported by a standard 34 which is mounted upon the base 10.

The frame 11' of the machine is supported solely by the casing 29' of the transmission mechanism 29 except for the fact that the lower ends 5 of the arms of the frame are provided with flanges 12' disconnected from the base 10 and provided with set screws 35 threadedly engaged therethrough and adapted to engage and clamp against the base 10. In other respects the device 10 is similar to the preferred form and the same parts may be recognized by corresponding reference numerals.

As illustrated in Fig. 4 the frame of the machine is set in the vertical position. If desired the 15 set screws 35 may be loosened so that the frame may be tilted to any degree in one or the other direction. When in the tilted position the set screws 35 may be driven down so as to engage against the top of the base 10 and so the frame 20 will be held in the adjusted inclined position.

While I have shown and described the preferred embodiment of my invention, it is to be understood that I do not limit myself to the precise construction herein disclosed and the right 25 is reserved to all changes and modifications coming within the scope of the invention as defined in the appended claims.

Having thus described my invention, what I claim as new, and desire to secure by United States Letters Patent is:—

1. An exercising machine, comprising a base, a speed reduction unit in a casing, and having a rear driving shaft and side driven shafts, a motor on said base connected with said rear driving 35 shaft, means for supporting said casing in angularly adjusted positions about the axis of said driving shaft, a vertical frame supported on said casing, a pair of lower pedals on the sides of said frame, a pair of upper pedals on the sides of said 40 frame, a transmission from said driven shafts for rotating said pedals, and means for holding said frame in various inclined positions on the axis of said driving shaft.

2. An exercising machine, comprising a base, 45 a speed reduction unit in a casing, and having a rear driving shaft and side driven shafts, a motor on said base connected with said rear driving shaft, means for supporting said casing in angularly adjusted positions about the axis of 50 said driving shaft, a vertical frame supported on said casing, a pair of lower pedals on the sides of said frame, a pair of upper pedals on the sides of said 55 frame, a transmission from said driven shafts for rotating said pedals, and means for holding said frame in various inclined positions on the axis of said driving shaft, said means for supporting the casing comprising a disc associated with one side of the casing for swivelly supporting the casing and a standard supporting 60 said disc upon said base.

3. An exercising machine, comprising a base, a speed reduction unit in a casing, and having a rear driving shaft and side driven shafts, a motor on said base connected with said rear driving 65 shaft, means for supporting said casing in angularly adjusted positions about the axis of said driving shaft, a vertical frame supported on said casing, a pair of lower pedals on the sides of said 70 frame, a pair of upper pedals on the sides of said frame, a transmission from said driven shafts for rotating said pedals, and means for holding said frame in various inclined positions on the axis of said driving shaft, comprising set screws en- 75

gaged through lower portions of said frame and adapted to engage against said base.

4. An exercising machine, comprising a base, a speed reduction unit in a casing, and having a rear driving shaft and side driven shafts, a motor on said base connected with said rear driving shaft, means for supporting said casing in angularly adjusted positions about the axis of said driving shaft, a vertical frame supported on said casing, a pair of lower pedals on the sides of said frame, a pair of upper pedals on the sides of said frame, a transmission from said driven shafts for rotating said pedals, and means for holding said frame in various inclined positions on the axis of said driving shaft, comprising set screws engaged through lower portions of said frame and adapted to engage against said base, the lower portions of the frame being provided with flanges for said set screws.
- 20 5. An exercising machine, comprising a base, a vertical frame on said base, a pair of lower pedals on the sides of said frame, a pair of upper pedals on the sides of said frame, and means for rotating said pedals, said vertical frame comprising a pipe fitting having vertical sides and a horizontal connecting top, said sides being provided with upper and lower horizontal pipes forming a casing for horizontal upper and lower shafts, upper and lower shafts in said horizontal pipes and extending from the side of the frame

and said upper and lower pedals being mounted upon the ends of said shafts, a transmission being engaged through one of the vertical sides of the frame for connecting the upper and lower shafts for unitary rotation, comprising a chain through the pipe and engaging sprockets fixed upon the shafts, and means for vertically adjusting the upper horizontal pipe for the purpose of controlling the tension of said chain, said upper horizontal pipe being connected with bushings 10 slidably upon the side arms of said frame, and said upper shaft engaging through said bushings and through elongated slots in said side arms.

6. An exercising machine, a base, a vertical frame on said base, and including vertical side 15 arms, each having a T fitting near its bottom, bushings slidably mounted on said side arms, a horizontal bottom pipe between said T fittings, a bottom shaft through said bottom pipe and T fittings, pedals on the ends of said shaft, a top 20 shaft through said top pipe and bushings and slots in the vertical side arms, pedals on the ends of the top shaft, means for driving the lower shaft, sprockets upon the top and bottom shafts and located within one of the side arms, a chain 25 over said sprockets and extending through the side arm, and means for holding said bushings in various adjusted positions for controlling the tension of said chain.
